UNITED STATES PATENT OFFICE.

LEON L. TRIPP, OF ALBANY, NEW YORK.

DESIGN FOR A BOAT.

Application filed April 2, 1928. Serial No. 26,099. Term of patent 14 years.

To all whom it may concern:

Be it known that I, LEON L. TRIPP, a citizen of the United States, residing at Albany, in the county of Albany and State of New York, have invented a new, original, and ornamental Design for Boats, of which the following is a specification, reference being had to the accompanying drawing, forming a part hereof.

What I claim is:

The ornamental design for a boat, as shown and described.

LEON L. TRIPP.
